CLAIM

The ornamental design for a pistol locker, as shown and described.

DESCRIPTION

FIG. 1 is a front elevational view of a pistol locker showing my new design;

FIG. 2 is a front perspective view thereof;

FIG. 3 is a bottom perspective view thereof; and

FIG. 4 is a side elevational view thereof, the opposite side being the same as the side shown.

The undisclosed rear surface of the pistol locker is conventionally flat and unornamented.

The numerals shown by means of broken lines are for illustrative purposes only.

Fig. 1.
